UNITED STATES PATENT OFFICE.

IRVING E. BROWN, OF SEBEWA, MICHIGAN.

TWINE-CAN FOR SELF-BINDING HARVESTERS.

1,119,238.

Specification of Letters Patent.

Patented Dec. 1, 1914.

Application filed February 2, 1914. Serial No. 816,077.

To all whom it may concern:

Be it known that I, IRVING E. BROWN, a citizen of the United States, residing at Sebewa, in the county of Ionia and State of Michigan, have invented a new and useful Twine-Can for Self-Binding Harvesters, of which the following is a specification.

My invention relates to improvements in twine-cans for self-binding harvesters, and 10 the objects of my improvement are: First. To facilitate the insertion of the balls of twine. Second. To make possible the tying of the ends of the balls after their insertion. Third. When the upper ball is exhausted, to facilitate raising the lower ball to the position formerly occupied by the upper ball, so that a new ball may be inserted beneath it and the tying process repeated. Fourth. To prevent the entanglement and consequent breakage of twine inside the can. I attain these objects by the mechanism illustrated in the accompanying drawing, in which all figures are views in perspective.

25 Figure 1 shows the twine-can partly opened; Fig. 2, partly opened and with the outer groove-bands removed; Fig. 3, closed and fastened; and Fig. 4, from the rear, with its opened door passing between the 30 body of the can and the bracket.

Similar letters refer to similar parts throughout the several views.

Before explaining the merits of my invention it is necessary to refer to the imperfections of the twine-cans now in use on all self-binding harvesters. In this type of can the twine-balls are inserted from the top, which is closed by a hinged cover. When the upper ball is exhausted, the 40 remaining ball must be extracted from the bottom of the can and held in the hands or laid in a precarious position on the harvester while a new ball is placed in the bottom of the can and its end tied to the 45 end of the ball before mentioned. This ball must then be placed in the can on top of the new ball—an operation which can not be performed without leaving unwound fifteen or eighteen inches of twine adjacent 50 the knot which connects the balls. Consequently when the upper ball is nearly exhausted, the torsion of the unwound twine near the knot, combined with the jar and vibration of the machine, frequently causes 55 entanglement and breakage of twine inside

the can. These annoyances are eliminated by my invention.

The top as well as the bottom of my twine-can, is joined solidly to the sides or barrel. The door A, sliding laterally in the 60 grooves B B, gives access to the interior, which is divided into two equal-sized compartments by the slotted shelf C, to which is riveted one end of the twine-latch D, in a manner which, when the door is open, permits the twine-latch to be moved laterally to the position shown in Fig. 2. The slot S, which in Fig. 1 is almost concealed by the twine-latch D, extends from the edge of the shelf C to its center, and is of sufficient 70 width to permit the passage of the knots which connect the balls of twine.

Fig. 1 shows the upper compartment empty, as when a new ball is to be inserted. By sliding the twine-latch D to the position 75 shown in Fig. 2, the twine-thread T may be withdrawn from the slot S in the shelf C, and the ball instantly transferred from the lower to the upper compartment. A new ball may then be placed in the lower compartment, as shown in Fig. 2, and its end tied to the end of the ball above it without unwinding one superfluous inch of twine. The twine-thread above the knot is then placed in the slot S, the twine-latch D is 85 closed, holding the thread securely in the slot, and the door A is closed, which holds the twine-latch D firmly in position. To prevent the twine-latch from slipping farther inward its outer edge is curved over 90 the edge of the shelf C.

In the door A are peepholes H H, which enable the operator, without opening the door, to tell when either compartment is empty.

A knob E is attached to the door A for convenience in opening and closing. When closed, the right-hand edge of the door A meets at top and bottom the shoulders V V of the narrow groove-bands F F (Fig. 2); 100 and a spring catch G, projecting through the side of the can directly behind the door A, engages the edge of the door and prevents it from opening until released by the pressure of a finger. Dotted lines indicate 105 the position of this spring catch inside the can.

Probably the cheapest method of constructing the grooves B B is shown in Fig. 2. Two bands I I, of the same width and 110

thickness as the bands J J, encircle the can, one at the top and one at the bottom. These bands are of about the thickness of the door A. Encircling the bands I I are the bands 5 F F, slightly thicker and much narrower except at the shoulders V V and for a short distance from them. Encircling the bands F F are the bands J J. Bands I and J thus form the sides of each groove B, while band 10 F forms the top and bottom of the upper and lower grooves and also gages the thickness thereof. Bands I and J may be constructed as a single wide band doubled lengthwise over band F. Rivets passing 15 through all three bands fasten them tightly to the can. A light casting, embodying the essential features of the bands, may form the grooves more satisfactorily at slightly greater cost.

20 The bracket K is riveted or bolted to the twine-can at points L; and when opened, the door A passes freely between the can and the vertical stem of the bracket. In Fig. 4 the bracket is shown connecting the can with 25 the frame of an Osborne grain harvester at M. The attaching feature of the bracket may be varied to meet the peculiarities of every make of grain and corn harvester.

I claim:

30 1. A twine-can for self binding harvesters, comprising a case having an opening at one side, and a slotted shelf positioned horizontally in said case between the top and bottom thereof, the slot in said shelf extending 35 from a side thereof adjacent the opening in the case, substantially as described.

2. A twine-can for self binding harvesters comprising a case having an opening at one side, a slotted shelf positioned horizontally 40 in said case between the top and bottom thereof, the slot in said shelf extending from a side thereof adjacent the opening in the case to substantially the center of the shelf and means for closing said slot at its 45 outer portion, substantially as described.

3. A twine-can for self binding harvest-

ers comprising a case having an opening at one side, a slotted shelf positioned horizontally in said case between the top and bottom thereof, the slot in said shelf extending 50 from a side thereof adjacent the opening in the case to substantially the center of the shelf, a door for closing the opening in the case, and means for closing the outer portion of the slot, said means being held in operative position by the door when it is in closed position.

4. A twine-can for self-binding harvesters, consisting of a cylindrical case closed at top and bottom and provided with a side 60 opening, a slotted shelf which divides the case into two compartments and to which is affixed a twine-latch, and a door which moves laterally in grooves to close the opening, all substantially as set forth. 65

5. A twine-can for self-binding harvesters, comprising a cylindrical case closed at top and bottom and provided with a side opening, a slotted shelf which divides the case into two compartments, a door which 70 moves laterally in grooves to close the opening, a fastening for the door, and a supporting bracket, which, without interfering with the action of the door, attaches the twine-can to the harvester, all substantially as 75 shown.

6. A twine-can for self-binding harvesters, comprising a cylindrical case closed at top and bottom and provided with a side opening, a slotted shelf which divides the 80 case into two compartments and to which is affixed a twine-latch, a door which moves laterally in grooves to close the opening, a fastening for the door, and a supporting bracket, which, without interfering with 85 the action of the door, attaches the twine-can to the harvester, all substantially as described.

IRVING E. BROWN.
